UNITED STATES PATENT OFFICE.

JOHN DANIEL, OF MILWAUKEE, WISCONSIN.

SAFETY STARTING-CRANK.

1,249,344.

Specification of Letters Patent. Patented Dec. 11, 1917.

Application filed March 15, 1916. Serial No. 84,265.

To all whom it may concern:

Be it known that I, JOHN DANIEL, a citizen of the United States, and resident of Milwaukee, in the county of Milwaukee, and State of Wisconsin, have invented new and useful Improvements in Safety Starting-Cranks, of which the following is a description, reference being had to the accompanying drawings, which are a part of this specification:

This invention has for its object to provide a safety starting crank for gas engines generally, but particularly for automobile gas engines, which will automatically become disconnected from the crank shaft whenever the engine back-fires, revolving the crank shaft in the opposite direction to the normal operating direction. Such back-firing of the engine is accountable for numerous accidents, the starting crank being forcibly turned by the engine in the direction contrary to that in which it was turned by hand and the suddenness of the operation causing it to fly out of the hand and swing around and strike the arm, frequently breaking same.

The present invention utilizes the reverse movement of the crank shaft to disconnect the starting crank therefrom, thus rendering it harmless.

Another object of this invention is to provide such a starting crank of simple and durable construction which will be inexpensive to manufacture and positive and efficient in its operation.

With the above and other objects in view, the invention consists in the safety starting crank as herein claimed and all equivalents.

Referring to the accompanying drawings, in which like characters of reference indicate the same parts in the different views,

Figure 1 is a sectional plan view of a safety starting crank constructed in accordance with this invention;

Fig. 2 is a front view thereof with the parts in their normal position for starting the engine, the crank, clutch and other parts being sectioned, and the crank member removed;

Fig. 3 is a similar view thereof with the parts in the positions assumed by them upon the occurrence of a backfire;

Fig. 4 is a sectional view on the plane of line 4—4 of Fig. 2;

Fig. 5 is a sectional view on the plane of line 5—5 of Fig. 2, showing the wedge lever in its normal position; and,

Fig. 6 is a similar view on the plane of line 6—6 of Fig. 3 showing the wedge lever in its position for disconnecting the operating crank from the crank shaft.

In these drawings 10 indicates the end of the crank shaft of a gas engine having the usual projecting pins 11 on opposite sides thereof for engagement with the inclined notches 12 of a coupling head 13 of a starting shaft 14 carrying a starting crank handle 15. While the invention is suitable for use with gas engines generally it is shown in the drawings as applied to the engine of an automobile, a portion of the frame 16 of the automobile being shown in dotted lines, and with the starting shaft 14 journaled therein as usual. A collar 17 is pinned on the starting shaft 14 and a coil spring 18 surrounding the starting shaft bears at one end against this collar and at the other end against the bearing on the frame 16 so as to normally hold the coupling head 13 out of engagement with the end of the crank shaft of the engine but permitting it to be engaged therewith when the crank handle is pushed rearwardly in the usual manner.

The crank handle 15 is not rigidly connected to the end of the starting shaft, as is usually the case, but it has a toothed clutch connection therewith and is normally held in its clutch engagement by spring pressure, though it may automatically be forced out of its clutch engagement upon the occurrence of a back fire.

The crank handle terminates in a clutch disk 19 which is loosely mounted on starting shaft 14 and is forced by a coil spring 20 at the end of the starting shaft against a ratchet disk 21 so as to engage complementary clutch teeth 22 and 23 on the clutch disk 19 and the ratchet disk 21 respectively.

The clutch teeth 22 project from the rear face of the clutch disk 19 while the clutch teeth 23 are formed between recesses in the face of the ratchet disk 21 so that the two disks may fit together face to face when the parts are in their normal positions, and the ratchet disk 21 is keyed and pinned to the starting shaft 14 in order that the crank handle may impart a longitudinal sliding movement thereto as well as a rotary movement, the first for en-

90

gaging the coupling head 13 and the latter for turning the engine shaft. Between the collar 17 and the ratchet disk 21 the starting shaft 14 is loosely fitted in a starting frame 24 which is movable with the starting shaft in its sliding movements toward and away from the crank shaft of the engine but is incapable of turning. For this purpose the starting frame 24 may have arms 25 with reduced ends slidably fitting in horizontal slots of brackets 26 which are adapted to be secured to the automobile frame 16 or other suitable support.

A stud 27 projects from the starting frame 24 and has pivotally mounted on it a cam member 28 which is held in a normal position by a spring pressed dog 29 on the frame 24 engaging a notch 30 in a flange 31 thereof. Pivotally mounted in a recess or opening through the cam member 28 is a pawl 32 which is normally pressed by a coil spring 33 into engagement with ratchet teeth 34 formed on the ratchet disk 21, the shape of the ratchet teeth and the end of the pawl being such that they offer no obstruction to the turning of the ratchet disk in one direction, the direction for starting the engine, but oppose the turning of the ratchet disk in the opposite direction. The opposition of the pawl to the turning of the ratchet disk in its counternormal direction is not for the purpose of preventing such movement but is for the purpose of imparting a swinging movement to the cam member 28, carrying its notch 30 out of engagement with the dog 29 and bringing another notch 35 into engagement therewith, as shown in Fig. 3. This swinging movement of the cam member carries the end of the pawl 32 out of the range of the ratchet teeth 34.

Another stud 36 on the frame 24 has pivotally mounted on it a wedge lever 37 which has an arc-shaped beveled blade portion 38 normally positioned in the groove between the disk 21 and the clutch disk 19 formed by the latter having its edge beveled. A lug 39 on the wedge lever 37, however, engages a shoulder 40 of the cam member 28 so that the swinging movement of the cam member incident to the back-firing of the engine causes said shoulder 40 to force the arm 39 ahead of it and thus swing the wedge lever 37 to force cam blade 38 between the ratchet disk 21 and the clutch disk 19, thus sliding the latter on the shaft 14 until its clutch teeth 22 become disengaged from the clutch teeth 23 of the ratchet disk, as shown in Fig. 6. The ratchet disk 21 and the shaft 14 are thus free to turn without turning the crank handle until the engine ceases to operate in its reverse direction. The wedge lever 37 is limited in its throw by engaging a yielding stop pin 41 which is spring pressed and slidably mounted in a lug 42 on the frame 24.

Said lever is held in its thrown position by

the arm 39 thereof coming into engagement with a concentric portion of the cam member 28.

In order to restore the parts to their normal operative position the dog 29 is depressed to disengage it from the notch 35, and the cam member 28 thus released is swung back to its normal position by pressing the finger against a spring pressed plunger 43 which is slidably mounted in the cam member and engages the tail end of the pawl so that the pawl is first swung to the dotted line position in Fig. 3 where it will clear the ratchet teeth 34. Further pressure on the plunger 43 will swing the cam member 28 to its normal position where the dog 29 will engage the notch 30. The shoulder 40 of the cam member passing beyond the arm 39 of the wedge lever permits the spring action of the stop pin 41 to withdraw the wedge lever from between the disks 21 and 19 so that the clutch engagement between the crank handle and the starting shaft is restored.

It will be understood that the presence of this invention does not interfere with the use of the starting crank in the ordinary way, the starting shaft becoming coupled with the engine crank shaft by a rearward pressure on the crank handle, and when this engagement is effected the crank shaft of the engine may be turned by revolving the crank handle as usual. Immediately upon the occurrence of a back firing of the engine which tends to drive the crank handle in the opposite direction from that in which it is being turned by hand, the first movement of the starting shaft in this reverse direction causes the ratchet to swing the cam member, and the latter to swing the wedge lever to a position where it will force the clutch disk out of its clutch engagement with the ratchet disk, thus disconnecting the crank handle from the starting shaft and keeping it disconnected until the parts are again restored to their normal condition. All danger from cranking the engine by hand is thus avoided by a mechanism which may be readily substituted for the ordinary crank mechanism without material alteration.

What I claim as new and desire to secure by Letters Patent is:

1. A starting crank for gas engines, comprising a movably supported frame, a starting shaft mounted on the frame and movable into and out of coupling engagement with an engine shaft, a crank handle loosely mounted on the starting shaft and having a clutch connection therewith, and means mounted on the frame operated by a turning of the starting shaft in a reverse direction for moving the crank handle out of its clutch engagement with the starting shaft.

2. A starting crank for gas engines, comprising a movably supported frame, a start-

ing shaft loosely mounted therein and movable into and out of coupling engagement with an engine shaft, a crank handle loosely mounted on the starting shaft and having 5 a clutch connection therewith, and means on the frame for moving the crank handle out of its clutch connection with the starting shaft operated by a rotary movement of the crank shaft in a reverse direction.

10 3. A starting crank for gas engines, comprising a movably supported frame, a starting shaft mounted thereon and capable of movement into and out of coupling engagement with an engine shaft, a crank handle having clutch connection with the starting shaft, a ratchet carried by the starting shaft, a pawl member mounted on the frame and engaging the ratchet and adapted to be moved by the ratchet when the starting 15 shaft turns in a reverse direction, and means operated by such movements of the pawl for disengaging the clutch connection between the crank handle and the starting shaft.

25 4. A starting crank for gas engines, comprising a suitably supported frame, a starting shaft mounted thereon capable of movement into and out of coupling engagement with an engine shaft, a ratchet disk on the 30 starting shaft provided with clutch teeth, a crank handle loosely mounted on the starting shaft and provided with a disk and clutch teeth, a spring for holding the crank handle in position to engage its clutch teeth 35 with the clutch teeth of the ratchet disk, a member pivotally mounted on the frame and having engagement with the ratchet teeth of the ratchet disk to be moved thereby when the crank shaft rotates in a reverse direction, and a wedge operated by the movements 40 of the said member to force its way between the two disks and thereby separate the clutch teeth to disengage the crank handle from the ratchet disk.

45 5. A starting crank for gas engines, comprising a suitably supported frame, a starting shaft mounted thereon capable of movement into and out of coupling engagement with an engine shaft, a ratchet disk fixed 50 on the starting shaft and provided with clutch teeth, a crank handle loosely mounted on the starting shaft and provided with a disk and clutch teeth, a spring for holding the crank handle in position to engage its 55 clutch teeth with the clutch teeth of the ratchet disk, a shouldered member pivotally mounted on the frame and having connection with the ratchet teeth of the ratchet disk and adapted to be moved thereby when 60 the starting shaft rotates in a reverse di-

rection, a wedge lever pivotally mounted on the frame and engaged by the shoulder of said member and moved between the two disks to force the clutch teeth out of engagement.

65

6. A starting crank for gas engines, comprising a suitably supported frame, a starting shaft mounted therein and capable of movement into and out of coupling engagement with an engine shaft, a ratchet disk 70 fixed on the starting shaft and provided with clutch teeth, a crank handle loosely mounted on the starting shaft and provided with a clutch disk having clutch teeth, a spring bearing on the crank handle to normally hold it in position for engaging its clutch teeth with the clutch teeth of the ratchet disk, a shouldered member pivotally mounted on the frame, a spring pressed pawl thereon engaging the teeth of the 75 ratchet disk, and a wedge lever pivotally mounted on the frame and engaging the shoulder of said member and having a wedge surface adapted to be forced between the two disks for disengaging the clutch 80 teeth upon a rotation of the starting shaft 85 in a reverse direction.

7. A starting crank for gas engines, comprising a suitably supported frame, a starting shaft mounted therein and capable of movement into and out of coupling connection with an engine shaft, a ratchet disk fixed on the starting shaft and provided with clutch teeth, a crank handle loosely mounted on the starting shaft and provided 90 with a clutch disk having clutch teeth, a spring bearing on the crank handle for holding it normally in position to engage its clutch teeth with the clutch teeth of the ratchet disk, a shouldered member pivotally 95 mounted on the frame, a spring pressed pawl thereon engaging the ratchet teeth of the ratchet disk, a dog engaging notches in the shouldered member for holding it in its different positions, a spring pressed releasing member in the shouldered member engaging the pawl for moving it out of the range of the ratchet teeth, a wedge lever pivotally mounted on the frame and engaged by the shoulder of the shouldered 100 member and having a wedge portion adapted to be forced between the disks to separate the clutch teeth, and a yielding stop on the frame engaged by the wedge lever.

In testimony whereof, I affix my signature, in presence of two witnesses.

JOHN DANIEL.
